No. 633,956.

Patented Sept. 26, 1899.

B. N. GOODALE.

SPINDLE GUARD FOR TEXTILE TREATING MACHINES.

(Application filed Jan. 6, 1899.)

(No Model.)

UNITED STATES PATENT OFFICE.

BENJAMIN N. GOODALE, OF SACO, MAINE.

SPINDLE-GUARD FOR TEXTILE-TREATING MACHINES.

SPECIFICATION forming part of Letters Patent No. 633,956, dated September 26, 1899.

Application filed January 6, 1899. Serial No. 701,330. (No model.)

To all whom it may concern:

Be it known that I, BENJAMIN N. GOODALE, of Saco, in the county of York and State of Maine, have invented certain new and useful 5 Improvements in Spindle-Guards for Textile-Treating Machines, of which the following is a description sufficiently full, clear, and exact to enable those skilled in the art to which it appertains or with which it is most nearly 10 connected to make and use the same.

This invention has relation to spindle-guards comprising means for preventing the accidental lifting of the spindles, with their revolving parts, (which consist of the whirls 15 and frictional surfaces,) from their steps or bearings when the spindle is in motion, while permitting the quick easy removal of said parts when the operator for any purpose desires to take them from the frame.

20 It is the object of this invention to provide means of the character mentioned which shall be thoroughly efficient for the purposes for which they are intended, be operated with ease, convenience, and quickness, and be out 25 of the way, so as not to interfere with the usual functions of the spindles or other parts of the machines in which the spindles may be used.

To these ends the invention consists in supporting a plate or bar in the rear of the spindles and providing the said plate with fingers or projections which when the plate is in normal position extend over the upper face of the whirl, but when the plate is moved from its normal position will be out of the way, so that 35 one or more of the spindles can be raised for the purpose of being oiled or cleaned, as hereinafter described and claimed.

In carrying out my invention I have found it to be satisfactory in construction and mode 40 of operation to provide the plate with inclined or radial slots and to support it in inclined position, holding it by a bolt and thimble or bushing passing through the slot. By this means the plate can be moved to normal position by its own gravity, and when moved out 45 of the way by a finger of the hand the fingers of the plate may not only be moved to one side, but backward out of the way as well. Again, under this last-mentioned form the inclined slots can readily be formed at one of their ends, so as to hold the plate locked back 50 or in out-of-the-way position.

Reference is to be had to the annexed drawings, and to the letters marked thereon, forming a part of this specification, the same letters designating the same parts or features, as the case may be, wherever they occur.

Of the drawings, Figure 1 is a front view of several spindles of a spooling or similar machine and a bolster-rail, the latter equipped with my improvements, and the upper part of some of the spindles being represented as broken off to better illustrate the invention. Fig. 2 is a sectional end view of what is represented in Fig. 1. Fig. 3 is a plan view of 65 the finger-plate as constructed in the present instance. Fig. 4 is a sectional detail view showing a manner in which the finger-plate is engaged and held.

In the drawings, *a* designates sleeve-whirl 70 spindles of a spooling-machine, and *b* designates what may be regarded as the bolster-rail of the same. As is well understood by those skilled in the art, the spindles *a* when released may be readily lifted out of their 75 steps (not shown) and bolster-rail for the purpose of cleaning, oiling, or repairs. When, however, the machine is in use and the spindles are running, it is necessary, in order to 80 guard against accident and insure desired results, that they should be prevented from lifting out of their steps or bearings, and when it is wanted that they should be lifted out it is desirable that this should be done 85 easily and quickly. It is, furthermore, necessary that the means for preventing their lifting out of place should be out of the way, so as not to obstruct the usual spooling or 90 spinning operations. To provide for these needs and to accomplish the purposes mentioned at the outset of this specification, I provide what I, for the purposes of this specification, term a "finger-plate" *c*, which has formed in it at suitable intervals inclined slots *d*, as shown in Fig. 3.

e designates brackets which are secured to the bolster-rail or any other suitable part of the machine and upon the upper faces of which there is a bar *f*, supported in inclined position, and beneath the said bar *f* I arrange the finger-plate *c*, so that it shall also extend in inclined position from the rear of the machine down toward the front. On the front edge of the finger-bar *c* there are formed pro-

sections or fingers *g*, which correspond when the finger-plate *c* is in normal position under the plate *f* with the spindles *a*, the said fingers *g* projecting over the upper faces of the whirls *h* on the spindles, around which the bands *b* run to drive them, it being understood that the whirls are compounded with the spindles or so connected with them as that the spindle and whirl move together.

i designates bolts which extend through the bar *f* and through the slots *d* in the finger-plate *c*, the said bolts having nuts *j* turned on their lower ends to hold the finger-bar *c* up in place. I prefer to place a thimble or bushing *k* around the shank *i* of the bolt, so that the finger-bar may be moved with greater freedom, and when it is desired to operate it and for the same purpose I prefer to interpose a washer *l* between the nuts *j* and the lower surface of the finger-bar *c*, as is best represented in Fig. 4.

It will now be understood that by making the slots *d* inclined or radial, as shown in Fig. 3, and leaving the said finger-bar loose between the washer *l* and the bar *f* the said finger-bar may be moved to one side and backward and when released will return to normal position by its own gravity. It is desirable when the bar *c* is moved longitudinally and backward to lock or hold it in the position to which it is thus moved, in which position it will release the spindles, so that they may be lifted out for any purpose, and to secure the holding of the bar in the position of unlocking or freeing the spindles I give to the inclined slot *d* at its lower end an upwardly-curved form, as shown at *m*. This allows the bolts *i* to drop in said upturned portion *m* and to hold the plate back. After the spindles released by the movement of the plate shall have been cleaned, oiled, or repaired the plate may be returned to normal position by simply pushing it back with the finger and moving it a little to one side, when it will immediately gravitate to normal position and remain in the latter position until again purposely moved out of the way. If the support for the plate is not inclined, as described, it may be moved to normal or operative position by hand.

It will be understood that in discussing the movement of the bar *c* I have reference at the same time to the fingers *g*, which extend over the whirl, since the said fingers are really the efficient parts of the bar *c* so far as the holding of the spindles in place or releasing them is concerned.

By this improvement very simple, inexpensive, and at the same time thoroughly-efficient

means are provided for preventing the lifting of the spindles, with their attached whirls, out of proper operative position, and means, too, which are out of the way, so as not to interfere with the other functions of the machine, and at the same time the means are capable of being readily operated by a single movement of the finger to release several spindles at a time, holding the plate out of the way in order that oiling or cleaning or repairs of the spindles can be rapidly done.

It is obvious that changes within the scope of mechanical skill may be made with my improvements without departing from the nature or spirit of my invention.

While I have illustrated my invention as applied to a form of sleeve-whirl spindle, it will of course be understood that the same is applicable to various kinds of spindles that are in use in machines of this kind.

Having thus explained the nature of the invention and described a way of constructing and using the same, though without attempting to set forth all of the forms in which it may be made or all of the modes of its use, it is declared that what is claimed is—

1. The combination, with the spindles and their whirls, of a movable plate provided with inclined slots and having fingers *g* adapted to project over the whirls, a support for the plate, and bolts projecting from the said support through the said slots, whereby the spindles are prevented from lifting from their proper operative position.

2. The combination, with the spindles and their whirls, of a movable plate provided with inclined slots and having fingers adapted to project over the whirls, a support to maintain the plate in inclined position, and bolts projecting from the said inclined supports through the said inclined slots, whereby the accidental displacement of the spindles is prevented.

3. The combination, with the spindles and their whirls, of a movable plate provided with inclined slots curved upwardly at their lower ends, as at *m*, and having fingers adapted to project over the whirls, a support to maintain the plate in inclined position, and bolts projecting from the said inclined supports through the said inclined slots.

In testimony whereof I have signed my name to this specification, in the presence of two subscribing witnesses, this 16th day of December, A. D. 1898.

BENJAMIN N. GOODALE.
